HAMMER MILL PROVIDED WITH MEANS
FOR DETACHABLY MOUNTING THE SIZ-
ING SCREENCharles F. Schutte, Buffalo, and Herman D.
Schutte, Snyder, N. Y.

Application September 15, 1948, Serial No. 49,404

2 Claims. (Cl. 241—86)

1

This invention relates to screen mills as in the case of our earlier U. S. Patent No. 2,328,170, and more particularly to screen mills or pulverizers and to further improved means for mounting exchangeable screen members thereon.

One of the objects of the invention is to provide an improved pulverizer of the hammer mill type having improved means incorporated therein for mounting the product sizing screen member thereof.

Another object of the invention is to provide a mill of the character described having an improved form of product screening element which is adapted to be mounted and demounted with respect to the mill frame in an improved manner.

Another object of the invention is to provide in a mill of the character described improved means for detachably locking the product screening member in mounted position relative to the mill frame.

Another object of the invention is to provide a mill of the character described having an improved arrangement for quickly and easily exchanging product screening members thereof so as to grade the mill product to different specifications.

Another object of the invention is to provide a mill for the purposes set forth hereinabove wherein in the procedure of exchanging the screen members thereof may be performed with improved safety and facility, without requiring the mill to be first shut down. Other objects and advantages of the invention will appear in the specification hereinafter.

In the drawings:

Fig. 1 is a side elevation of a hammer mill of the invention with a portion of the casing broken away to show the interior thereof, and with the screen member thereof shown in both mounted and demountable positions;

Fig. 2 is a fragmentary top plan of the machine of Fig. 1; and

Fig. 3 is an enlarged view of a detail of Fig. 1, showing the screen positioning and latching mechanism in different positions of operation.

The drawings illustrate the invention in connection with a hammer mill of the type that is adapted particularly for grinding or pulverizing grain or other commodities, and the mill comprises essentially a box-like base or frame 10 carrying bearing blocks 12 at opposite sides thereof for rotatably supporting the rotor shaft 14. The rotor 16 is carried by the shaft 14 and in turn mounts a series of hammers 18 which are pivotally connected to the rotor so as to extend

2

radially therefrom. Heads 20 are carried by the hammers 18 to receive the majority of the wear in connection with processing of the mill feed. An upper casing or cover portion 22 is mounted upon the base 10 so as to complete the mill enclosure, and a mill feed inlet spout 24 is arranged to discharge the mill feed through an inlet port 26 of the mill cover so as to discharge the mill feed in the form of a continuous stream 10 into the mill casing and upon the rapidly rotating rotor and hammer unit while traveling in substantially the same direction of movement.

The end wall portion of the mill casing substantially opposite to the mill feed chute is preferably reinforced by a wearing plate 30 in the region of impingement of the mill feed stream against the casing wall resulting from the momentum of the mill feed and the impact of the rotor hammers thereagainst. Thus, the wearing

plate 30 may constitute an integral portion of the mill casing wall 32, or may be simply a detachable wearing plate mounted therewith so as to be renewed from time to time as may be required. The product screening element of the 20 mill comprises an arcuately shaped screen member 34 such as a perforated sheet metal plate or a woven wire fabrication, or the like; and the screen member is mounted to extend transversely of the mill frame structure 10 between opposite side wall portions thereof and so as to complement and closely conform to the lower arc of the mill hammer orbit. Consequently, in the case of certain mills of the prior art the screen elements thereof corresponding to the member 34 of the present invention are arranged to be

35 mounted relative to the other mill elements when in operative position so as to be disposed in substantially the same manner of arrangement as is illustrated by the solid line showing thereof in Fig. 1 of the present drawing. However, the prior art arrangements usually involve in addition some provision for dropping the screen member 40 downwardly away from operative position preliminary to removal of the screen member from the mill frame in connection with screen exchange procedures as are required to turn out products of various specifications. Such arrangements have invariably involved the use of

45 relatively complicated screen support and exchange devices; the use of which usually requires the mill to be stopped before the screen members may be exchanged, and through use of which the time required for screen exchange is very substantial.

50 In the case of our prior patent we disclosed an improved arrangement accommodating with-

55

Fig. 1 of the present drawing. However, the prior art arrangements usually involve in addition some provision for dropping the screen member

40 downwardly away from operative position preliminary to removal of the screen member from the mill frame in connection with screen exchange procedures as are required to turn out products of various specifications. Such arrangements have invariably involved the use of

45 relatively complicated screen support and exchange devices; the use of which usually requires the mill to be stopped before the screen members may be exchanged, and through use of which the time required for screen exchange is very substantial.

50 In the case of our prior patent we disclosed an improved arrangement accommodating with-

55

Fig. 1 of the present drawing. However, the prior art arrangements usually involve in addition some provision for dropping the screen member

drawal and replacement of screens through an opening at the front end of the mill, and removable means for levering and latching the screens in operative positions. The present invention provides further improvements in the screen manipulating and locking mechanisms in such mills.

As in the case of our prior patent, in accord with the present invention the opposite side wall portions of the base frame 10 are provided with inwardly extending ledges 36 which are of substantially circular form in side view and disposed concentrically of the center of rotation of the rotor-hammer unit. A second set of inwardly extending ledges 38 are arranged to extend inwardly from the side wall portions of the base frame and are arranged in substantial parallelism with and are relatively closely spaced relative to the corresponding ledges 36 in the region of the rear half of the mill. Thus, a relatively narrow space as indicated at 40 is provided between the corresponding ledge members 36-38 at each side of the mill in the rear portion thereof for slide-fitting reception of the corresponding side edge portions of the screen member 34 therebetween. Thus, it will be understood that in the rear portion of the mill the ledge members 36-38 at opposite side wall portions of the mill frame will cooperate to position the rear portion of the screen 34 in operative position and in an attitude of concentricity with respect to the axis of the rotor rotation.

At the forward end portion of the mill, however, the ledge members 36-38 are formed so as to diverge further away from the positions of the corresponding ledge members 36 so as to provide a funnel-like space as indicated at 42 (Figs. 1 and 3) between corresponding of the ledges 36-38 within which the corresponding end portion of the screen member 34 is free to move in directions radially of the axis of rotor rotation. The screen member 34 is formed to be of resilient nature and to have a tendency to "set" in a curvature having a radius substantially larger than the radius of the orbit of the hammer mill rotation.

Thus, any one of a number of screens such as the member 34 may be selected and mounted singly within the mill by initially disposing it in pick-a-back relation upon the casing wall 32 as illustrated by broken lines in Fig. 1. Then the lower end of the screen member is inserted into the funnel-like spaces between the ledges 36-38, whereupon the screen member may be slid downwardly and under the rotor hammer assembly as its leading end portion proceeds rearwardly of the mill and is guided between the closely spaced ledges 36-38 into its final operative position. During this initial installation procedure the trailing end portion of the screen 34 will of course bear away from the inner ledges 36-38, due to the tendency of the screen member to normally set at a curvature somewhat flatter than the curvature of the ledges 36. As will now be explained the screen positioning and locking mechanism of the invention is then brought into action to complete the installation of the screen member in operative position.

The positioning and locking member of the present invention differs from that of our prior Patent and comprises essentially a lever device including a transverse plate portion 50 having a looped handle 52 extending at a right angle therefrom. The forward edge of the plate 50 is formed with a beaded nose 54 so as to engage in

roller bearing contact relation against the end portion of the screen. The plate of the locking device is formed at opposite sides with ear portions 58-58 which receive bearing pins 60-60 extending inwardly from the mill casing side walls.

The lever plate and bearing pin elements are so constructed and arranged that when the plate 50 is pivoted as to the position thereof shown in Fig. 1 and the broken line position thereof in Fig. 3, the nose portion 54 thereof forcibly pushes against the upper end portion of the screen 34 so as to elastically deform the latter into contiguous conformity with the casing ledges 36 throughout the entire length of the screen. Thus, the screen is held by the lever plate 50 in screen-operative position. A latch 62 is pivotally mounted as at 64 to extend from a front cover plate portion 66 of the mill base 10, for latching the handle 52 in the position thereof shown in Fig. 1, thereby holding the lever plate 50 in its screen locking position.

To release a previously mounted screen for replacement thereof whenever it is required to substitute another screen without requiring the mill to be shut down, it is only necessary to lift the latch 62 and to pull outwardly upon the lower end of the handle 52.

The lever plate 50 thereupon pivots upon the pins 60-60, as to the solid line position of the lever plate shown in Fig. 3, whereupon the adjacent end of the screen 34 will move into the funnel-like space between the opposed ledges 36-38 in response to the elastic forces of the screen material. The free end of the screen may then be grasped by the operator of the mill and the screen withdrawn by simply lifting it upwardly as to the broken line position thereof in Fig. 1, whereupon the screen may be removed completely from the mill and a substitute screen of generally similar form but having the required size of apertures may be inserted, as in the manner of mounting described hereinabove. It will be appreciated that a particular feature and advantage of the arrangement of the invention resides in the fact that due to the natural resiliency and tendency of the screen members to open to curvatures of greater diameter than the curvature of the mill rotor orbit when the screens are released from restraint against the ledges 36-38, the screen members will be thereby automatically adapted to move freely about the enlarged curvature of the end wall 32 of the mill casing. Otherwise, the screen members would clamp and wedge against the end wall 32 of the casing in such manner as to prevent the mounting and dismounting procedure as described hereinabove. It will also be appreciated that the screen positioning and locking mechanism of the invention provides, in combination with the other elements of the device, an improved method and means for quickly and positively positioning and locking the screen in operative position upon the mill, and for quickly releasing the screen in connection with dismounting operations; and that the entire screen exchange procedure may be accomplished in only a few seconds while the mill rotor is kept running. Thus, there is a substantial saving of time and motor restarting power which would otherwise be lost in connection with the screen changing process.

A further important feature of the present invention resides in the provision of a guard plate 70 which comprises a curved metal sheet shaped to complement the curvature of the cas-

20

70

ing cover plate portion 30 and to normally lie externally thereagainst as illustrated by the solid line showings thereof in Figs. 1-3. The plate 70 is vertically slotted as indicated at 72 to accommodate a bolt 74 which extends from the cover plate 32 and carries a wing nut 75 for locking the plate 70 in various positions of vertical adjustment relative to the cover plate 32. The slot through the guard plate 70 is arranged so that following release of the screen as to the solid line positions thereof in Fig. 3, the wing nut 75 may be loosened so that the guard plate will drop down into the opening 42, such as to the broken line position of the guard plate 70 as shown in Fig. 3. This plate thereupon functions as a barrier against accidental access by the operator's hand to positions within reach of the mill hammers, incidental to operator manipulation of the released screen and/or installation of a substitute screen as explained hereinabove. Then, upon completion of a subsequent installation of a substitute screen into the solid line position thereof in Fig. 3, the guard plate 70 will be retracted to its raised position and the lever handle 52 then depressed so as to force the screen to contract into operative position against the ledges 36; whereupon the lever handle 52 will be locked by the latch 62 and feeding of the mill continued.

It will also be appreciated that in view of the novel arrangement and operation of the machine of the invention the screen exchange process may be conducted without possibility of danger to the operator of the machine, and with utmost facility and convenience to the operator thereof in every respect; and that although only one form of the invention has been shown and described in detail, it will be apparent to those skilled in the art that the invention is not so limited but that various changes may be made therein without departing from the spirit of the invention or the scope of the appended claims.

What is claimed is:

1. In a sizing mill, a bottom frame, a rotor mounted upon said frame for rotation within a circular orbit, a semi-cylindrical screen mounted upon said frame to substantially complement the lower half of said rotor orbit, said screen being elastic and having a tendency to normally set in a curvature having a radius substantially greater than the radius of said rotor orbit, a top cover mounted upon said bottom frame to complete enclosure of said rotor at the upper side thereof, said cover being shaped to generally conform to the orbit of said rotor and divergent from the curve of said frame at one end to provide a screen change opening therebetween, ledge means extending from said bottom frame to slidably receive and locate one end portion of said screen so as to be in operating position coaxial with said rotor orbit, said ledge means being adapted to limit centripetal displacement of said screen throughout its entire extent to a cylindrical operating position coaxial with said rotor orbit, and lever means including a handle and a mill closure plate hingedly mounted upon said frame to engage said screen at the other end portion thereof, said mill closure plate being formed with a screen engaging portion for slide bearing engagement against said screen for elastically deforming said screen into said operating position by clamping said other end portion of said screen upwardly and centripetally into said operating position against the elastic forces of said screen, and a locking device associated with

said handle for detachably locking the latter in screen operating position, whereby said screen may be mounted in operating position within said mill by disposing it in inverted attitude upon said top cover and then sliding said screen downwardly and under said rotor into engagement with said ledge means at the rear end of said mill, and then levering the trailing end portion of said screen into constricted curvilinear form as limited by said ledge means against the elastic force of said screen into a coaxial attitude with respect to said rotor orbit and locking said screen in said operating position by means of said locking device, and a guard plate, operable mounting means for mounting said guard plate on said top cover, said mounting means being so constructed and arranged as to permit said guard plate to be moved from its normal position on said cover and clear of said screen change opening down to a position extending between said rotor orbit and the released position of said other end portion of said screen.

2. In a sizing mill, a bottom frame, a rotor mounted upon said frame for rotation within a circular orbit, a semi-cylindrical screen mounted upon said frame to substantially complement the lower half of said rotor orbit, said screen being elastic and having a tendency to normally set in a curvature having a radius substantially greater than the radius of said rotor orbit, a top cover mounted upon said bottom frame to complete enclosure of said rotor at the upper side thereof, said cover being shaped to generally conform to the orbit of said rotor and divergent from the curve of said frame at one end to provide a screen change opening therebetween, ledge means extending from said bottom frame to slidably receive and locate one end portion of said screen so as to be in operating position coaxial with said rotor orbit, said ledge means being adapted to limit centripetal displacement of said screen throughout its entire extent to a cylindrical operating position coaxial with said rotor orbit, and lever means fulcrum-mounted upon said frame to engage said screen at the other end portion thereof and adapted to be actuated manually for levering said other end portion of said screen against the elastic forces thereof into said operating position coaxial with said rotor orbit, and locking means associated with said lever means for detachably locking the latter in operating position, and a guard plate, operable means for mounting said guard plate on said top cover clear of said screen change opening but permitting said guard plate to be slidable substantially vertically thereon into said screen change opening subsequent to release of said lever locking means and expansion of said screen toward said normal set curvature.
